UNITED STATES PATENT OFFICE

FRITZ STRAUB AND WALTER ANDERAU, OF BASEL, SWITZERLAND, ASSIGNORS TO THE FIRM SOCIETY OF CHEMICAL INDUSTRY IN BASLE, OF BASEL, SWITZERLAND

AZO-DYESTUFFS CONTAINING METAL AND PROCESS OF MAKING SAME

No Drawing. Application filed August 21, 1928, Serial No. 301,165, and in Switzerland September 10, 1927.

The present invention relates to the manufacture of azo-dyestuffs containing metal. It comprises the process of making these azo-dyestuffs, the azo-dyestuffs themselves, and 5 the material that has been dyed with these dyestuffs.

Monoazo-dyestuffs which contain groups capable of combining with mordants have frequently been converted into complex metal 10 compounds and such complexes may contain one or several metals, see for instance French Patent No. 483,019.

Polyazo-dyestuffs containing groups capable of combining with mordants have not 15 hitherto been converted into complexes which contain more than one metal. If such a polyazo-dyestuff had to be converted into a complex which contained only one metal, this could be brought about merely by treating the 20 finished dyestuff with the agent yielding metal or by producing the dyestuff in presence of the agent yielding metal.

By the present invention polyazo-dyestuffs containing groups capable of combining with 25 mordants are converted in an advantageous manner into simple or mixed metal complexes, not by treating the finished polyazo-dyestuff but by treating the intermediate dyestuff obtained during the manufacture of the 30 polyazo-dyestuff with an agent yielding metal, and if necessary causing an agent yielding metal to act further on the finished dyestuff. These agents yielding metal may contain one or several metals. In the different phases of 35 the metallization the same or different metals may be used. It is also possible to use in the separate phases different metals in succession.

Furthermore, polymetallic complexes of 40 polyazo-dyestuffs can also be made by treating the finished polyazo-dyestuff with agents yielding metal containing more than one metal or by introducing several metals in succession into the dyestuff molecule. The dyestuffs produced are mainly suitable for dyeing 45 vegetable fibres and silk. It has been found that such products are obtained if an agent yielding metal and containing more than one metal is allowed to act on a suitable monoazo-dyestuff, which contains a so-called cotton component, or by introducing 50

into such a dyestuff different metals in succession. The term cotton component means such components which impart substantive properties to the azo-dyestuffs produced therewith. Particularly suitable are those 55 dyestuffs which derive from the 2-amino-5-hydroxynaphthalene-7-sulfonic acid and the N-derivatives thereof, benzidines or para-diamines, or which contain the thiazol ring.

The complexes made by means of several 60 metals are different from the products which are produced by mixing the several metal complexes; the new products can be obtained mixed with single metal complexes according to the proportion in which the metal compounds may be used.

It has also been found that by introducing several metals into the dyestuff molecule of polyazo-dyestuffs which do not contain a cotton component but which nevertheless already 70 possess a slight affinity for cotton there can be observed a considerable increase of the cotton affinity.

In the several phases of the production of the polyazo-dyestuffs the couplings may be 75 performed in presence of agents which yield metals.

The following examples illustrate the invention, the parts being by weight:—

Example 1

46.1 parts of 5:5'-dioxy-2:2'-dinaphthylamine-7:7'-disulphonic acid are dissolved in 700 parts of water together with 30 parts of calcined sodium carbonate and are coupled 80 with the diazo-solution from 14.3 parts of 4-chloraminophenol. The red dyestuff of the formula

obtained by salting out as usual, is dissolved 85 in 6000 parts of hot water and there are added 25 parts of crystallized copper sulphate in the form of a concentrated solution, and the whole is heated for 1/2 hour on the water-bath while stirring. The dyestuff assumes a 90 violet tint and is quantitatively precipitated 100

by common salt. In water and concentrated sulfuric acid it dissolves to a violet solution. In sodium carbonate solution or dilute caustic alkali solution to a blue red solution. It dyes cotton red-violet in a dye-bath containing 5 Glauber's salt.

The new dyestuff is now dissolved or suspended in 1000 parts of sodium carbonate solution of 5 per cent. strength and coupled further with the diazo-solution from 14.3 parts of 10 4-chloroaminophenol. The mono-copper-compound, isolated as usual, is dissolved in 6000 parts of water and the solution is boiled with 30 parts of Cr_2O_3 in the form of a 15 chromium fluoride solution of 7.8 per cent. strength for 24 hours in a reflux apparatus. There is obtained a dyestuff which when dry 20 is a bronze powder, which dissolves in concentrated sulfuric acid and in water to a violet solution and in sodium carbonate solution or in caustic soda solution to a blue-violet solution. It dyes cotton fast blue-violet in a dye-bath containing Glauber's salt.

25 *Example 2*

The tetrakisazo-dyestuff obtained by combination of 22.2 parts (1 mol.) of tetrazotized ortho-ortho'-dichloro-benzidine with 64.8 parts (2 mol.) of 2-amino-5-hydroxynaphthalene-7-sulfonic acid in acid solution, subsequently coupling the intermediate product thus obtained with 29 parts (2 mol.) of diazotized 4-chloro-2-amino-1-phenol of the formula

is dissolved or suspended in 7000 parts of boiling water and this solution or suspension is mixed, while stirring, with 25 parts of crystallized copper sulfate in the form of a 50 saturated solution. After some minutes, there are added 15.6 parts of Cr_2O_3 in the form of a chromium fluoride solution of 7 per cent. strength and the whole is heated 55 in a reflux apparatus, while stirring, for 36 hours. The dyestuff formed appears in finely suspended condition as a violet substance. It is filtered. When dry it is a dark powder which in water and dilute sodium carbonate solution is hardly or sparingly 60 soluble to a violet solution. In concentrated sulfuric acid it dissolves to a violet solution.

Example 3

The dyestuff made from 46.1 parts of 5:5'-dioxo-2:2'-dinaphthylamine-7:7'-disulfonic

acid and 28.6 parts of diazotized 4-chloroaminophenol of the formula

is dissolved in the form of a press cake in 6000 parts of hot water and 7.6 parts of Cr_2O_3 in the form of a chromium fluoride solution of 7.8 per cent. strength are added. The whole is heated for 24-30 hours in a reflux apparatus and there are added to the mixture, while it is still hot, 25 parts of crystallized copper sulfate and heating is 80 continued for some time at 100° C. The original red dyestuff has now become blue and is in large part separated from the solution. By addition of sufficient common salt 85 it is wholly precipitated and is then filtered. The dyestuff is a blackish powder. It dissolves in water, sodium carbonate and dilute caustic soda solution to a blue solution and in concentrated sulfuric acid also to a 90 blue solution. In a dye-bath, which is neutral or alkaline with sodium carbonate and contains Glauber's salt, cotton is dyed blue tints which exhibit good properties of fastness.

95 *Example 4*

The press cake obtained from 46.1 parts of 5:5'-dioxo-2:2'-dinaphthylamine-7:7'-disulfonic acid and 28.6 parts of diazotized 4-chloroaminophenol according to Example 3 100 is dissolved in 6000 parts of hot water and after addition of 25 parts of crystallized copper sulfate in the form of a concentrated solution is boiled, while stirring well for some minutes. There are then added 30 parts of Cr_2O_3 in the form of a chromium fluoride solution of 7.8 per cent. strength and the whole 105 is heated for 25 to 30 hours in a reflux apparatus. By addition of common salt to the still warm solution the dyestuff is precipitated. It is filtered and dried and is then a 110 blue-grey powder which dissolves in concentrated sulfuric acid, water, sodium carbonate solution and caustic soda solution to blue 115 solutions. A neutral or alkaline dye-bath containing Glauber's salt dyes cotton fast reddish blue tints.

By varying the proportion of copper to chromium other like products are obtained.

120 *Example 5*

An acetic acid suspension of 24 parts of 2-amino-5-hydroxynaphthalene-7-sulfonic acid is mixed with 25 parts of crystallized 125 copper sulfate and, after the latter is dissolved, with the diazo-solution from 27 parts of 2-aminophenol-4:6-disulfonic acid. When coupling is complete (in an acid medium) the whole is heated to 95° C. and after 1/2 130

hour the intermediate dyestuff is precipitated by addition of common salt and hydrochloric acid.

This intermediate product is dissolved in 5 200 parts of hot water and 25 parts of calcined sodium carbonate are added, whereupon the intermediate product is combined with the diazo-compound from 14 parts of 4-chloro-2-aminophenol. There is produced a 10 dyestuff with properties essentially similar to those of the dyestuff named above. It is separated and dissolved in 4000 parts of water, the solution is boiled in a reflux apparatus for 36 hours with the addition of 15.6 15 parts of Cr_2O_3 in the form of a chromium fluoride solution of 7 per cent. strength. The product is worked up in known manner and there is obtained a dyestuff which dissolves in water and dilute alkalies to a violet solution 20 which is essentially bluer than that above-named. The dyestuff dyes silk in an acetic acid bath violet tints. Concentrated sulfuric acid dissolves it to a violet solution.

If the dyestuff obtained as described in the 25 first paragraph of this example is dissolved in 3000 parts of hot water and the solution is mixed with 25 parts of crystallized copper sulfate, and the whole then warmed for some time on the water-bath, a dyestuff is produced 30 which is soluble in water and in dilute alkalies, as well as in concentrated sulfuric acid, to a violet solution. The dyestuff dyes silk in an acetic acid bath violet tints.

Example 6

35 55 parts of crystallized sodium sulfide, 46 parts of chromium hydroxide paste containing 9.1 per cent. of Cr_2O_3 and 10 parts of sulfite cellulose liquor of 50 per cent. strength, 40 are mixed together and stirred with 35 parts of the sodium salt of the dyestuff from 6-nitro-2-diazo-1-phenol-4-sulfonic acid and β -naphthol of the formula

45 50 in the form of a paste of 63 per cent. strength. The whole is then heated gradually to 80° C. whereby the dyestuff is caused to pass into solution, after which heating is continued for 12-15 hours at 90-100° C. The mass is 55 neutralized with hydrochloric acid, heated to 80° C., the dyestuff is redissolved again by means of sodium carbonate, the solution filtered, again made neutral and salted out.

60 65 The dyestuff thus obtained is dissolved under neutral conditions in 300 parts of hot water, the solution is mixed with 7 parts of sodium nitrite and, after cooling to 5° C., there are added 100 parts of ice-cold hydrochloric acid of 10 per cent. strength, and

the whole is stirred for about 1/2 hour until the reaction for nitrite vanishes. This diazo-body is now combined with 13.8 parts of salicylic acid in a solution alkaline with sodium carbonate. The coupling is finished 70 after a short time, whereupon the new dyestuff may be completely separated by means of common salt. When dry it is a blackish powder which dissolves in water and dilute alkalies to a blackish violet solution and dyes 75 silk black violet tints.

For the purpose of obtaining the iron compound of this dyestuff it is dissolved in 800 parts of hot water, 62 parts of crystallized sodium acetate are added and 12 parts of acetic acid of 100 per cent. strength, and finally a ferric chloride solution of 4 per cent. strength containing 12 parts of Fe_2O_3 . The whole is heated for some time in a reflux apparatus whereupon the iron compound is 85 gradually precipitated and is filtered. In order to remove ferric oxide which may have been formed from the dyestuff, the latter is dissolved with addition of caustic soda solution in cold water, the solution filtered and the filtrate, after neutralization, precipitated by means of common salt. The dyestuff when dry is blackish powder which dissolves in water and dilute alkalies to a blackish-violet solution; it dyes silk in an acetic acid 90 bath black-violet tints.

Example 7

The dyestuff from 15.4 parts of diazotized 100 5-nitro-2-aminophenol and 31.5 parts of 2-phenylamino-5-hydroxynaphthalene-7-sulfonic acid, of the formula

is dissolved in 8000 parts of hot water. There 110 are added in succession a saturated solution of 6.25 parts of crystallized copper sulfate and a saturated solution of 7 parts of crystallized nickel sulfate, and the mixture is heated for some minutes to boiling while stirring. There is then added the aqueous solution of 15.6 parts of Cr_2O_3 in the form of 115 chromium fluoride solution of 4 per cent. strength and the whole is heated for 36 hours in a reflux apparatus. At the end of this time the dyestuff is salted out by means of 200 parts of common salt and filtered. When dry it is a bronze dark powder which dissolves in water, sodium carbonate or dilute caustic soda solution to a pure blue solution 120 and dyes cotton in a bath which is neutral or alkaline with sodium carbonate and contains Glauber's salt, pure blue tints. Concentrated sulfuric acid dissolves the dyestuff 125 to a violet solution.

Similar dyestuffs are obtained if instead of phenylaminonaphthalenesulfonic acid the equivalent quantity of 2-(para-tolylamino)-5-hydroxynaphthalene-7-sulfonic acid of the formula

10

or 2-benzylamino-5-hydroxynaphthalene-7-sulfonic acid of the formula

60

22 or 2-(para-phenetidino)-5-hydroxynaphthalene-7-sulfonic acid of the formula

or 2-(ortho-anisidino)-5-hydroxynaphthalene-7-sulfonic acid of the formula

35

83 or 2-(2'-methoxy-4'-methyl)-phenylamino-5-hydroxynaphthalene-7-sulfonic acid of the formula

45

45 or 2-(4'-hydroxy-3'-carboxyl)-phenylamino-

5-hydroxynaphthalene-7-sulfonic acid of the formula

70

are used. By addition of 10-15 parts of crystallized sodium acetate to the chroming bath the duration of boiling can be somewhat shortened. 75

Example 8

The dyestuff made from 15.4 parts of diazo-
tized 5-nitro-2-aminophenol and 31.5 parts
of 2 phenylamino-5-hydroxynaphthalene-7-
sulfonic acid or 32.9 parts of 2-paratholyl-
amino-5-hydroxynaphthalene-7-sulfonic acid
is dissolved in 750 parts of hot water and 4.18
parts of crystallized copper sulfate in the
form of a concentrated solution are added at
the boiling point. The whole is then further
heated to the boiling point, while stirring
well, and after $\frac{1}{4}$ hour there are added 1.56
parts of Cr_2O_3 in the form of a chromium
fluoride solution of 5.2 per cent. strength
and heating is continued for 36 hours in a re-
flux apparatus. The original blue red solu-
tion has changed in the course of this time to
a violet blue. By addition of 200 parts of
common salt the dyestuff is precipitated quan-
titatively. When dry it is a bronze powder
which dissolves in water, sodium carbonate
solution or caustic alkali solution to a blue
solution. In concentrated sulfuric acid to a
blue-red solution. It dyes cotton blue tints
in a bath which is neutral or alkaline to sodium
carbonate and contains Glauber's salt.

By using more copper and less chromium 105 or more chromium and less copper similar products are obtained.

In the following table there are described some further examples of polyazo-dyestuffs containing several metals:—

No.	Coupling component	Diazotizing component	Metals	Shades of dyeings

20 What we claim is:—

1. A process for the manufacture of azo-dyestuffs in substance containing chromium and copper, consisting in treating azo-dyestuffs containing lake-forming groups and having affinity for cotton, with agents yielding copper and chromium.

2. A process for the manufacture of azo-dyestuffs containing chromium and copper, consisting in treating polyazo-dyestuffs having hydroxyl-groups in ortho-position to the azo-groups and deriving from cotton components, with agents yielding copper and chromium.

35 3. The azo-dyestuffs in substance containing chromium and copper obtained by treating azo-dyestuffs containing lake-forming groups and having affinity for cotton, with agents yielding chromium and copper, which products, the constitution of which is not known, form dark blue to blue-violet powders, dissolving in water and dilute alkalies to dark red-blue to blue solutions, dyeing cotton, viscose, and silk violet to blue and

45 blue-grey tints.

4. The azo-dyestuffs containing chromium and copper obtained by treating polyazo-dyestuffs having hydroxyl-groups in ortho-position to the azo-groups and deriving from 50 cotton components, with agents yielding chromium and copper, which products, the constitution of which is not known, form dark-blue to blue-violet powders, dissolving in water and dilute alkalies to dark red-blue to blue solutions, dyeing cotton, viscose, and silk violet to blue and blue-grey tints.

In witness whereof we have hereunto signed our names this 7th day of August 1928.

FRITZ STRAUB.

WALTER ANDERAU.
